METHOD OF AND MEANS FOR TREATING
CLUBFOOTPhilip R. Brachman and Orville C. Sonntag,
Chicago, Ill.

Application January 17, 1946, Serial No. 641,676

13 Claims. (Cl. 128—80)

1

This invention relates to the treatment of talipes or clubfoot and more particularly to apparatus for the treatment thereof.

An object of the invention is the provision of novel and improved apparatus adapted to minimize, if not to obviate, the necessity of using uncomfortable, unsightly and more or less immobilizing casts or splints hitherto employed after the usual preliminary corrective manipulation of deformed feet.

Another object of the invention is the provision of such apparatus which, while permitting independent and correlated foot movements about axes substantially parallel to the legs between improved positions relative to the deformed positions of a patient's feet and positions at substantially the normal limits of movement of the feet in a direction from the improved positions opposite those of the deformed positions, prevents movements from the improved positions toward the deformed positions.

A further object of the invention is the provision of such apparatus which enables an afflicted user to move the feet to and fro relative to each other in a manner simulating walking.

Another object of the invention is the provision of such apparatus which, while preventing movement of a deformed foot between an improved position and the deformed position, permits exercising the foot and leg by movements thereof outside the range between the deformed and improved positions.

The invention has as a further object the provision of such apparatus which is readily and easily applicable to and removable from the feet of a user.

Yet another object of the invention is the provision of such apparatus having an adjustable prescription angle; i. e., the angle defined by the longitudinal axes or center lines of the feet of a user in a prescribed improved position and from which neither foot alone is movable toward its deformed position.

Another object of the invention is the provision of such apparatus wherein the prescription angle is variable sufficiently to adapt the apparatus for the treatment of talipes of the type wherein the forward ends of the feet are turned outwardly relative to each other, and of the type wherein they are turned inwardly toward converging relationship.

A further object of the invention is the provision of such apparatus wherein a pair of shoes is removably attached to connecting means adapting each shoe of the pair for limited relative pivotal movements about a center at the sole of that moving shoe and about a center at the sole of the other shoe.

Other objects of the invention will be apparent from the following description and the accom-

panying drawings disclosing by way of illustration a preferred embodiment of the invention.

In the accompanying drawings wherein like reference characters designate like parts throughout the several views:

Fig. 1 is a front elevation of apparatus for the treatment of talipes embodying some of the features of the invention;

Fig. 2 is an up-side-down plan view of the apparatus shown in Fig. 1 with portions shown broken away or otherwise removed and shows a prescription angle for the type of deformity wherein the heel-to-toe axes or center lines of the deformed feet converge, and, in broken lines, shows relative displacement of one of the shoes about an axis at the other shoe;

Fig. 3 is a fragmentary view similar to Fig. 2, but shows the connections adjusted for a prescription angle for the type of deformity wherein the heel-to-toe axes or center lines of the deformed feet are divergent;

Fig. 4 is a view similar to Fig. 2 with portions removed and shows the shoes at the other limits of their independent pivotal movement;

Fig. 5 is a side view of the novel apparatus and shows the connecting means removably attached to the shoe; and

Fig. 6 is a fragmentary cross-section taken substantially along the lines 6—6 of Fig. 5.

The deformity known as clubfoot manifests itself sometimes as talipes equinus or calcaneous wherein the lower surfaces of the heel and ball of an afflicted foot are not co-planer, but instead, when the ball of the afflicted foot engages a plane surface, the heel is spaced from that surface, or in other words, a portion of the foot apparently is displaced about a line extending transversely of the foot. At other times the deformity is of the type, talipes varus or valgus wherein an afflicted foot is turned inwardly or outwardly with its inner or outer longitudinal side raised with reference to a horizontal surface engaged by the other longitudinal side or margin of the foot; or in other words, wherein the afflicted foot apparently is turned about a substantially horizontal line extending forwardly at the lower end of the leg. Not infrequently the deformity appears as talipes equino-varus wherein the abnormality is a combination of those already described. All too frequently the deformity includes still other abnormalities alone or combined with one or more of the foregoing such as that wherein the forwardly extending longitudinal center line of each or either foot is turned outwardly or diverges abnormally from that of the other foot or wherein the outwardly extending longitudinal center line of each or either foot is turned inwardly or converges abnormally toward that of the other foot.

Treatment of the deformity has hitherto fre-

60

quently extended over a period of years and involved surgery and, whether or not surgery was practiced, casts or splints of plaster of Paris for holding each deformed foot in an improved position. Such treatments usually follow a preliminary treatment requiring several weeks. That preliminary treatment is employed while the bones of the afflicted infant are still relatively pliable and consists generally in repeated manipulation and massage whereby to coax or urge each deformed foot toward normal position. The bones, tendons and muscles of an infant's feet being more or less pliable and undeveloped are generally responsive to such treatment, but have not sufficient strength to maintain the afflicted foot in an improved or the normal position against the forces exerted by the abnormal tendons, tissues, and muscles in a direction urging the foot from its improved or normal position toward its deformed position.

The successive casts or splints, with or without the effects of surgery, are intended to counteract the effects of such forces tending to return the deformed foot toward its abnormal position. Those casts or splints, besides being inconvenient to apply, expensive, and unsightly, impair mobility, blood circulation, and muscular development. Hence, such treatment, while more or less efficacious in straightening the deformed foot, frequently results in shrivelled, shrunken, or shortened legs and feet, which are almost as unsightly and otherwise undesirable as the deformity itself. Thus, however successful the conventional treatment may be in relieving the specific deformity, it frequently produces other physical impediments which are almost as great handicaps as the deformity itself would have been without correction.

According to the present invention, novel apparatus, applicable to the feet of the afflicted infant following the preliminary treatment, is provided for maintaining each deformed foot in the improved position resulting from such preliminary treatment, preventing it from returning to or toward its deformed position from that improved position, and yet enabling a user to move either or both of his feet in the opposite direction between the improved position and a position at substantially the normal limit of movement (Fig. 4), and to move his feet to and fro (Fig. 2) simulating walking. Thus the afflicted foot and the leg may be developed by exercise and the patient need not be immobilized during treatment.

Such novel apparatus is preferably adjustable to permit, where desired, periodic changes in the angle made by the forwardly extending longitudinal axes of the feet as the improvement progresses, whether that angle is greater or less than the normal or ultimately desired angle between such axes, and to adapt the apparatus for use in treating talipes or clubfoot wherein the forward end of either or each afflicted foot diverges or converges toward that of the other foot. When made as prescribed by the physician and, if adjustable, adjusted by him or according to his prescription, the novel apparatus is easily applicable to and removable from the feet of the afflicted individual following the usual preliminary treatment as described hereinabove.

Illustrative of the invention, a presently preferred embodiment thereof is shown in the accompanying drawings. As therein illustrated, the novel apparatus comprises a pair of shoes 11 and 12 of usual construction, each with a sole

13 and a lace 14 or other suitable means for holding the shoe on the foot of an individual. Such shoes when arranged on the feet and laced, draw the inner sole surfaces snugly against the soles of the encased feet. Those shoes are pivotally connected together by novel means which cooperates therewith to hold the ball and heel portions and the longitudinal margins of each foot in substantially co-planar relationships and for preventing pivotal movement of either foot between an adjustable improved position and the deformed position, while permitting pivotal movement from and toward the improved position in a direction therefrom opposite that of the deformed position.

In the illustrated embodiment of the invention, the novel connecting means includes sole-rigidifying means 15 and 16 respectively attachable to the soles 13 of the shoes 11 and 12. Those sole-rigidifying means 15 and 16 are applicable to the shoes for the right and left feet, respectively. Otherwise they are identical. Each comprises a pair of metal plates 17 and 18 stamped or otherwise formed in size and shape to correspond to the size and shape of the sole of the shoe to which it is attachable. Those two plates 17 and 18 of each pair are spaced apart in superposed relationship by a forward block or spacer 19 and a rearward block or spacer 21.

The spacer blocks 19 and 21 of each sole-rigidifying means are formed of any suitable material in any desired shape. Preferably they are of leather, rubber, rubber composition, or other material which is non-absorbent and resists shrinkage. Each spacer block 19 preferably conforms to the configuration of the forward or toe end of a pair of the superposed plates 17 and 18 and is interposed therebetween at their forward ends. Each spacer block 21 is interposed between a pair of the plates 17 and 18 at the outer superposed margins thereof near the forward ends of their heel portions.

Each pair of superposed plates 17 and 18 with the interposed spacer blocks 19 and 21 is held in assembled relationship by screws, bolts, or other suitable securing means 22 extending through the plate 18 and anchored in or to the plate 17, some of them passing through each of the spacer blocks 19 and 21. When so assembled, the novel sole-rigidifying means serve to resist flexing of the shoe soles, when attached thereto, under such forces as those tending to return a deformed foot to a position wherein the lower surfaces of the heel and ball are not co-planar as in talipes equinus, and a position wherein either of the longitudinal margins of the lower surface is raised relative to the other of such margins, as in talipes varus. In addition, such sole-rigidifying means serve to carry the mounting means 20 for novel link means 21 and cooperate therewith so to connect the shoes 11 and 12 that each is pivotally movable relative to the other about a pivot attached to its sole, and likewise about a pivot at the sole of the other shoe.

Various link means may be employed to provide such pivotal movement. In the illustrated embodiment of the invention, such link means comprises a radius bar or link 23 and a correction limit bar or link 24 each stamped or otherwise formed from a suitable metal of a thickness to be slidably receivable between the plates 17 and 18 of the sole-rigidifying means 15 and 16.

The radius bar 23 is pivotally secured at one end between the plates 17 and 18 of the sole-rigidifying means 15 by suitable pivoting means

such, for example, as a shouldered bolt 25 passing through the radius bar and threadedly anchored in a threaded aperture (not shown) in the plate 17, as shown in Fig. 4 and Fig. 5, or through the plate 18 and the radius bar and threadedly anchored in the plate 17 as shown in Fig. 2. The radius bar 23 extends from that pivotal connection with the sole-rigidifying means 15 laterally to an identical connection at its opposite end on a shouldered bolt 26 anchored in the plate 17 of the sole-rigidifying means 16.

Where desired, a plurality of selectable anchoring positions is provided for the opposite ends of the radius bar 23 by the provision of a series of spaced threaded apertures 27 in the plate 17 of each of the sole-rigidifying means 15 and 16, extending from adjacent the spacer block 21 transversely inwardly of the heel portion, and respectively registering apertures 28 in the plate 18 of sufficient diameter as shown in Fig. 2 and Fig. 5 to permit the passage therethrough of the heads of the bolts 25 and 26, or, as shown in Fig. 2, of fastening means of lesser diameter than the heads of those bolts. Thus the pivot bolts 25 and 26 are easily removable and replaceable and the distance between the heels may be fixed and adjusted by the physician or at his direction.

The correction limit bar 24 has formed, in its opposite ends, longitudinally extending elongated apertures 29. At one end that correction limit bar extends between the plates 17 and 18 of the sole-rigidifying means 15, and suitable means such for example, as a shouldered bolt 31 either passes through the aperture 29 in the correction limit bar and is threadedly anchored (not shown) in the plate 17 as shown in Fig. 5 or, as shown in Fig. 2, passes through the plate 18 and the aperture 29 and is threadedly anchored in the plate 17. Like the radius bar 23, the correction limit bar 24 extends from such connection with the sole-rigidifying means 15 laterally to a position between the plates 17 and 18 of the sole-rigidifying means 16 where an identical connection is made at its opposite end on a shouldered bolt 32 passing through the elongated aperture 29.

Where desired, a plurality of selectable positions is provided for each of the shouldered bolts 31 and 32 by the provision of a series of spaced threaded apertures 33 in the plate 17 of the respective sole-rigidifying means 15 and 16, extending from adjacent the inner margins thereof transversely outwardly along lines forwardly of the apertures 27, and respectively registering apertures 34 in the plate 18 of sufficient diameter, as shown in Fig. 5, to permit the passage therethrough of the heads of the bolts 31 and 32, or, as shown in Fig. 2, of fastening means of lesser diameter than the heads of those bolts. Thus the bolts 31 and 32 are easily removable and replaceable and cooperate with the elongated apertures 29 to limit the pivotal movement of the sole-rigidifying means about the bolts 25 and 26, respectively associated therewith, and the limits of the pivotal movement are adjustable as directed and prescribed by the physician.

The novel link means just described is adapted not only to permit and control desirable movements of the feet, but also to cooperate with the sole-rigidifying means for preventing the turning of either foot about a substantially forwardly directed, horizontal fulcrum or axis or the elevation of one longitudinal margin relative to the other as occurs in talipes varus, and for holding the forward (ball) and rear (heel) portions of

each sole of the shoes to which they are attached in co-planar relationship.

In accordance with the preferred embodiment of the invention, the assembled sole-rigidifying 5 and link means constituting the novel connecting means already described are so attached to the shoes 11 and 12 as to be more or less readily removable and attachable to other shoes of the same or a different patient. The soles of the 10 shoes 11 and 12 are arranged on the faces of the plates 17 opposite the plates 18 of the sole-rigidifying means 15 and 16, respectively. With the shoes and connecting means so arranged, wood screws 35 are inserted through apertures (not shown) in the plates 17 and threaded into the 15 respectively adjacent soles of the shoes 11 and 12. Preferably the screw holes in the plates 17 for those screws 35 are countersunk to receive the screw heads in flush relationship with the outer or lower faces of the plates 17. If desired, apertures 36 are provided in the plates 18, registering with the screws 35 and of sufficient diameter to permit the insertion and removal of the attaching screws 35 after the plates 18 are secured to the 20 corresponding plates 17.

As shown in Figs. 5 and 6, the toe or forward end of each sole-rigidifying means is, where desired, provided with a suitable toe strap or cap 37 of, for example, metal secured in any usual manner preferably to the plate 18 and forming above the plate 17 a toe-receiving recess or cavity into which the toe of the appropriate shoe is inserted. Such a toe cap cooperates with suitable means at the rear or heel portion of each sole-rigidifying 25 means to obviate the use of the wood screws 35 for removably securing the connecting means to the 30 shoes 11 and 12.

The presently preferred heel securing means as 35 illustrated in Figs. 5 and 6 comprises for each sole-rigidifying means 15 and 16, a pair of clamp members 38 threaded at their lower ends on threaded end portions 39 of a pin or shaft 41 rotatably carried intermediate the threaded portions 39 in bearing lugs 42 struck up from the 40 plate 18 at its rear or heel end. The clamp members 38 of each pair extend upwardly above the pin 41 to adjacent the lower face of the plate 17 and outwardly beyond the opposite side edges thereof, thence upwardly a distance above the plate 17 slightly greater than the thickness of the heel of the shoe. At their upper ends, the clamp members of each pair are turned inwardly for engagement on the heel of the shoe. One end of each pin 41 is preferably flattened or formed 45 of polygonal shape as at 43 to facilitate adjustment of the associated pair of clamp members 38 to and from clamping engagement with shoe heels of different widths.

After the toe of each shoe is inserted in the toe 50 cap 37, the corresponding pin 41 is operated to move the associated clamp members 38 into or from clamping engagement with the heel of the shoe for attaching the connecting means to or removing it from a pair of shoes.

The sole-rigidifying means 15 and 16 cooperate 55 with the link means 20 adjustably connected as already described to each of them and extending therebetween to determine an adjustable prescription angle indicated at Rx in Fig. 2. The 60 prescription angle Rx is the angle made by and included between the longitudinal axes or center lines of the sole-rigidifying means arranged at the respective limits of their lengths of movement toward the deformed position of the patient's 65 feet for which the novel apparatus is prescribed.

Fig. 2 shows an Rx angle for a deformity of the type wherein the forward or toe ends of the feet are convergent. By the preliminary treatment, the feet are manipulated to the improved position indicated in that view of the drawing and the novel apparatus is arranged on the feet. When the apparatus is so applied to the feet, the engagement of the bolts 31 and 32 with the inner ends of the respective apertures 29 prevents the simultaneous movement of both feet, from the position illustrated in Fig. 2 inwardly toward the deformed position, about the pivot bolts 25 and 26, and each foot resists the movement of the other foot from that improved position toward the deformed position.

If a different prescription angle is desired or if it is desired to change the prescription angle due, for example, to improvement of the afflicted individual, then either the bolts 31 and 32 are removed and inserted through the elongated apertures 29 into the appropriate anchoring apertures 33 in the plates 17 or the bolts 25 and 26 are removed and are inserted into the appropriate anchoring apertures 27 of the respective plates 17 or both of the described adjustments may be employed to obtain a desired prescription angle and to vary it as may be necessary or desirable. For example, Fig. 3 shows the bolt 31 anchored in the outer aperture 33 of the plate 17. By moving both the bolts 31 and 32 to the outer anchoring aperture 33 of the respective plates 17 substantially the same prescription angle as that shown in Fig. 2 is obtained, but the angle of Fig. 3 is for the deformity of the type wherein the forward or toe ends of the feet are divergent. Thus the bolts 31 and 32 engage the outer ends of the respective elongated apertures 29, preventing simultaneous movement of the feet from the position of Fig. 3 outwardly toward the deformed position. With that arrangement as described in connection with Fig. 2, each foot resists the movement of the other foot from the improved position toward the deformed position.

While as already described, the novel apparatus prevents movement of the deformed feet from the prescribed or attained improved position toward the deformed position, it will be observed by reference to Figs. 2, 3, and 4 that the patient or user may nevertheless move his feet independently of or simultaneously with each other, from the selected improved position outwardly from the position of Fig. 2 to the position shown in Fig. 4 or, as the case may be, inwardly from the position of Fig. 3 to a position (not shown) which like the Fig. 4 position is at substantially the normal limit of movement of the feet in a direction from the improved position opposite that of the deformed position, and return the feet to the prescribed improved position. In so moving, the sole-rigidifying means 15 and 16 rotate about the axes of the respective bolts 25 and 26. The elongated apertures 29 cooperate with the bolts 31 and 32 to permit and control such movement between the limits just described.

By reference to Fig. 2 it will also appear that either of the sole-rigidifying means 15 and 16 and, hence the respective feet to which they are attached, is swingable forwardly and rearwardly of the other about the axes of the bolts 25 and 31 on the one hand and on the other hand about the axes of bolts 26 and 32. While in Fig. 2 by the broken lines only the sole-rigidifying means at the left is shown as having been swung rearwardly about the axes of the bolts 25 and 31, it will be obvious that the broken lines

may represent an original position and the full line position of the sole-rigidifying means at the right in that view of the drawing would then illustrate a forward swinging at that sole-rigidifying means. Since the connections at the opposite ends of the link means 20 to the sole-rigidifying means 15 and 16 are identical, then obviously the sole-rigidifying means at the left in Fig. 2, like that at the right, is adapted for forward swinging movement, that at the right like the one at the left is adapted for rearward swinging movement, as just described. The spacer blocks 19 and 21 serve to limit such movement of the feet. Thus a wearer is enabled to simulate walking. It should be observed that during such movements simulating walking the prescription angle is maintained. The exercise attainable with the novel apparatus as thus far described promotes development of afflicted feet while they are being held out of their deformed positions.

Being anchored at their opposite ends to the sole-rigidifying means, the connecting links 23 and 24 resist any tendency of either foot of a wearer to turn in such manner as to move either longitudinal margin upwardly or downwardly relative to the other longitudinal margin of the same foot. Since the elevation or depression of either end of a foot relative to the other end of the foot results in a twisting force or torque being applied to the connecting links, they resist such movements. Thus the novel apparatus may be employed to prevent the feet of an individual afflicted with talipes varus, valgus, equinus, calcaneus, and equino-varus from returning from an attained improved position to the deformed position.

We claim:

1. In apparatus of the class described, the combination with a pair of shoes, of means for maintaining the ball and heel portions of one shoe of said pair in substantially coplanar relationship, and means for restricting movement of said one shoe about an axis substantially perpendicular to the sole of that shoe to a range having as one limit the normal limit of foot movement in one direction and as its other limit of movement in the other direction a predetermined position between the normal limits of foot movement about said axis, said shoes being connected by means enabling swingable movement of said one shoe about an axis spaced from the first mentioned axis.

2. In apparatus of the class described, the combination with a pair of shoes, of means for preventing one shoe of said pair from turning about a line substantially parallel to the longitudinal axis of the shoe sole, and means for restricting movement of the said one shoe about an axis substantially perpendicular to the sole of that shoe to a range having as one limit the normal limit of foot movement in one direction and as its other limit of movement in the other direction a predetermined position between the normal limits of foot movement about said axis, said shoes being connected by means enabling swingable movement of said one shoe about an axis spaced from the first mentioned axis.

3. In apparatus of the class described, the combination with a pair of shoes, of means for maintaining the ball and heel portions of a foot in a shoe of said pair in substantially co-planar relationship and the longitudinal margins of the lower surface of said foot in substantially normal, relative positions, and connecting means for said

shoes effective to limit movement of the foot in one of said shoes about an axis substantially perpendicular to and intersecting the sole of that shoe to a range having as one limit the normal limit of movement in one direction and as its other limit of movement in the other direction a predetermined position between the normal limits of movement of the foot about said axis, said connecting means being effective to limit swingable movement of said one shoe about a pivot perpendicular to and intersecting the sole of the other shoe to a predetermined range.

4. In apparatus of the class described, the combination with a pair of shoes, of means for preventing relative displacement of the forward and rear sole portions of a shoe of said pair, means for preventing relative displacement of the longitudinal sole margins of said shoe with respect to a surface parallel to the shoe sole, and means for fixing said shoe against pivotal movement about an axis vertical to the sole of that shoe at one side of a predetermined position, the last said means permitting limited swinging movement of said shoe about said axis at the other side of said predetermined position, and coincidentally permitting limited swinging movement of said shoe about another axis vertical to the other shoe, said axis being horizontally spaced from one another.

5. In apparatus of the class described, the combination with a pair of shoes arranged in side-by-side relationship for application to the feet of a user, of means for resisting displacement of either end of each shoe relative to the other shoe about a transverse axis and of either longitudinal margin of each shoe relative to the other shoe about a longitudinal axis, means extending between said shoes for holding the shoes in spaced relationship, means connecting each said shoe to the last said means in any of a plurality of positions for pivotal movements about a vertical axis, and means for adjustably restricting the pivotal movement of each shoe about the vertical axis thereof to a range having as one limit substantially the normal limit of foot movement about a vertical axis in one direction and as its other limit an adjustable position intermediate the first said limit and the other normal limit of foot movement about a vertical axis in the other direction.

6. In apparatus of the class described, a pair of shoes, sole-rigidifying means secured to the sole of each of said shoes, link means pivotally connected respectively at opposite ends to said sole-rigidifying means and cooperating therewith to hold said shoes in spaced relationship and adapting each shoe for independent and correlated movements about the vertical axis associated with the other shoe, means for limiting the pivotal movements in opposite directions, and means for adjusting the limits of pivotal movements of each shoe.

7. In apparatus of the class described, a pair of shoes, means for spacing said shoes apart, means pivotally connecting said shoes to said spacing means in any of a plurality of positions for pivotal movement of each shoe about a vertical axis associated with the other shoe, means for limiting the pivotal movements of each shoe in opposite directions, and means for adjusting the limits of pivotal movement of each shoe.

8. In apparatus of the class described, a pair of shoes, means for spacing said shoes apart, pivot means connecting each said shoe to the

last said means and providing separate pivotal axes vertical to the soles of the respective shoes, the spacing means and said pivot means adapting a said shoe for pivotal movements about both said axes, and means for limiting the extent of pivotal movement of said shoe about each of said axes.

9. In apparatus of the class described, a pair of shoes, means subjacent the soles of said shoes for spacing said shoes apart, and pivot means under the soles of the respective shoes connecting them to the last said means and adapting each said shoe for limited pivotal movement about both said pivot means.

10. In apparatus of the class described, a pair of shoes, metal plates each of sole shape for the respective shoes and attached thereto, pivot members anchored in the respective plates at the heel portions thereof, and link means having opposite ends pivoted to said plates by said pivot members and having a slidale connection with each said plate forwardly of the pivot member anchored therein, each said slidale connection being adapted to limit pivotal movement of the associated shoe and metal plate about the pivot member anchored therein.

11. In apparatus of the class described, the combination with a pair of shoes, of connecting means including means for spacing said shoes apart and adapting them for limited pivotal ambulatory movements about a pair of spaced parallel axes, and means for removably securing said shoes on said connecting means over the respective axes with the shoe soles at right angles thereto.

12. A method of treating clubfoot, which comprises arranging shoes on the feet of the afflicted individual, fixing one of said shoes for coincidental limited pivotal movements about two spaced axes intersecting respectively the soles of both shoes, and limiting said pivotal movement about the axis intersecting said one shoe to a predetermined position between the deformed position of the foot and its normal limit of turning movement about the last-mentioned axis.

13. In apparatus of the class described, the combination with a pair of shoes of means for connecting said shoes, said connecting means comprising spaced pivotal connections, one associated with each shoe, means for enabling free turning movement of each of said shoes about its respective pivotal connection, and means for limiting such free turning movement about each connection whereby limited ambulatory movement of the shoes is permitted.
